UNITED STATES PATENT OFFICE.

DANIEL ROBERT CAMEERON, OF VANCOUVER, BRITISH COLUMBIA, CANADA.

GRAIN DOOR.

Application filed April 15, 1922. Serial No. 552,832.

To all whom it may concern:

Be it known that I, DANIEL ROBERT CAMERON, a subject of the King of Great Britain, residing at the city of Vancouver, in the Province of British Columbia, Canada, have invented certain new and useful Improvements in Grain Doors, of which the following is a specification.

My invention relates to improvements in grain doors, and the object of my invention is to provide a door for use on grain cars capable however of being used with equal facility on cars, trucks, or wagons for the carrying of other material, which door is of the simplest construction, possesses great strength and durability, is adapted when unlocked to open outwardly under the pressure of the grain or other bulk material within the car, and which is so constructed and arranged that it may be operated with great convenience from the side of the car opposite to the discharging side or from a point remote from the car such as from a suitable position within an elevator building. A further object is to devise a door of this character which is adapted to form an integral part of a box car and may be swung inwardly to lie flat on the inner wall of the car when not in use so that it does not interfere with the stowage or unloading of any other merchandise or commodities with which the car may be loaded at the time, other than grain.

I attain these objects by the construction illustrated in the accompanying drawings in which

Fig. 1 is a side elevation showing the lower or main door closed.

Fig. 2 is a transverse section on the line 2-2 of Fig. 1.

Fig. 3 is a plan view of the unlocking ratchet mechanism.

Fig. 4 is a fragmentary view in perspective of the inside of a car illustrating the embodiment of my invention therewith.

Fig. 5 is a reduced side elevation showing both the lower and upper doors closed.

Fig. 6 is a vertical section on the line 6-6 of Fig. 5.

Fig. 7 is an enlarged view in perspective of the key.

Similar numerals of reference indicate similar parts throughout the several views.

In the drawings, 1 indicates the outside

wall of a typical grain car, 2 the doorway, 3 and 4 the vertical standard posts on opposite sides of the doorway, 5 the bottom frame sill, 6 the top frame piece of the doorway, 7 one of the rafters positioned at mid-width of the doorway, 8 the inner lining of the car, and 9 the floor.

The main door of the car consists of two vertical door sections 10 and 11 formed out of thin steel plate hinged at their outer edges to the standards 3 and 4 so that they are capable of swinging outwardly, as indicated by the dotted lines in Fig. 2, or inwardly to lie flat on the lining 8, as indicated by the dotted lines in Fig. 4 illustrating one of the main doors thus swung inwardly. The door hinges 12 and 13 are substantially the full height of the door sections. These two door sections when swung together into the closed position do not meet at their inner edges but are spaced apart a suitable distance and the inner ends of the sections are bent first outwardly to form vertical side flanges 14 and 15 and then bent to form vertical flanges 16 and 17, lying at right angles to the side flanges, the flanges 14 and 16 of one section being opposed to the flanges 15 and 17 of the other section, from which it will be seen that when both sections are closed, there exists in effect a groove or channel 18 between them, the sides of the groove being formed by the side flanges 14 and 15 and the bottom of the groove by the right angled flanges 16 and 17, the opposing edges of which flanges are however spaced apart, all as shown particularly in Figs. 1 and 2. The inner edges of the sections 10 and 11 are closer together at their lower ends than they are at their top ends and as the flanged construction just described is formed parallel to the said edges the groove 18 tapers downwardly and inwardly so that it is a wedge-shaped groove, the upper end or mouth of which is the wide end.

Each door section 10 and 11 is reinforced by bars 19-20-21 and 22-23-24 respectively, of any suitable cross section, preferably flat, and the inner ends of these bars are formed as eyed ends, 25-26-27 and 28-29-30 having vertical eyes 31, as indicated in Fig. 2. When the sections are closed the eyed ends of opposite bars overlap each other, that is, 25 overlaps 28, 26

overlaps 29, and 27 overlaps 30, with the eyes 31 of the overlapping ends registering, and these eyes are made of a size to receive slidably, pins 32, 33 and 34 secured into a key member 35 adapted to fit slidably the groove 18.

This key 35 is formed channel-like and tapers complementary to the taper of the groove 18 being made so that its sides 36 and 37 fit snugly the walls of the groove when seated therein, and the pins 32, 33 and 34 are positioned so that they will fully engage their respective eyes 31 when the key is in place. These pins are preferably secured to the key by being bent over at one end at right angles and threaded, the threaded ends, 38 in Fig. 4, being passed through the key and secured by nuts 39 and 40, there being a nut on each side of the key so that the pins may be adjusted if required. The middle pin 33 is made shorter than the upper and lower pins so that when these two latter pins are entered into their respective eyes the middle one will enter its eye without any further guidance. At its upper end the key is provided with an eyed member 41 adapted to receive a hook 42, as hereinafter described, and opposite the eye 41 in the side 36 of the key is a hole 43 which registers with a corresponding hole 44 in the side flange 15 of the section 11, through which holes a pin 45 may be passed to engage the eye 41 and thus detachably hold the key to the section as shown in Fig. 5 and also prevent the hook 42 from being inserted in the eye 41 until the pin 45 is withdrawn, as the hook is only intended to be engaged when the key is to be withdrawn from the groove 18. The pin 45 is connected to section 11 by a chain 46.

The main door sections 10 and 11 are mounted so as to be slightly clear of the floor 9 of the car so that their lower edges will not catch on any obstructions in the floor and the space 47 between the lower edges of the door and the floor is closed by flaps 48, 49 and 50 of fabric or any other suitable material which are secured to the inside of each section and the key respectively by means of small bolts 51, the door flaps 48 and 49 meeting one another at their inner ends and overlapping the key flap, as shown in Fig. 4, so that no grain can escape through the space 47. These flaps, however, would not be absolutely necessary when other material or commodities such as coal, furniture, or the like were carried and in that case they may be removed by taking out the bolts 51 and stored for further use with grain.

In order to increase the amount of grain or the like which may be loaded into the car a supplemental or upper smaller door is provided which also consists of two door sections of thin steel 52 and 53 hinged at

their outer edges to the standards 3 and 4 by hinges 54 and 55 and the construction of these door sections is substantially similar to the construction already described with reference to the lower doors, as the sections are reinforced with bars 56-57 and 58-59 having their inner ends eyed and overlapping, a divided tapering groove 60 similar to groove 18 being also provided between the upper sections when closed in which may be slidably fitted a tapering key 61 similar to key 35, having pins 62 and 63 adapted to engage the eyes of the overlapping ends of the bars 56-58 and 57-59, the key being also fitted with an eye 64 at its upper end similar to the eye 41 of the main door key. The only difference between the upper door arrangement and that of the lower one is that whereas the side flanges of the lower groove are turned outwardly the side flanges of the upper groove are turned inwardly so that the upper groove is not in vertical alignment with the lower groove but lies behind it so that the lower key may be raised in front of the upper groove and key and clear of them while the upper door is closed. When both the upper and lower doors are closed the lower ends of the upper door overlap the upper ends of the lower door with the upper key lying against the lower key and in this position there is a space between the keys equal to the depth of the sides of the upper key but this space is entirely closed by a semi-circular strip 65 secured to the back of the lower key and over which the lower end of the upper key fits.

In order to enable the doors to be opened from the side opposite to the discharging side a barrel member 66 is rotatably mounted on one side of the rafter 7, its shaft extending through to the opposite side of the rafter and being operated by a pawl 67 and ratchet 68 actuated by means of a lever 69 having an extension lever 70 foldably connected to its free end. 71 indicates a locking pawl to prevent return movement of the ratchet. The extension 70 may be folded and supported on the main lever 69, resting on a side lug 72, and the main lever may be swung up out of the way as indicated by the dotted lines in Fig. 4, and supported on a bracket 73 secured to the rafter. There is enough side play in the main lever assembly to permit it to be passed over the end of the bracket 73 and supported on the top of the same, and the same applies to the lever 70 and lug 72. To the barrel 66 is secured one end of a rope 74 the free end of which passes over a sheave 75 rotatably carried in a bracket 76, which bracket is provided with a flat plate end 77, which fits up into a slot 78 formed in the top frame piece 6 of the doorway, there being a similar slot 79 in the frame piece of the opposite

doorway, being held therein by a bolt 80 passed through the slot and the plate, while to the free end of the rope is connected the hook 42 hereinbefore mentioned, which hook when not in use is held up to the frame piece 6 in any suitable manner. The sheave 75 is provided with a plurality of holes 81 adapted to receive the hook of a snatch block, as will be referred to later.

10 82 indicate latches hingedly connected at one end, as at 83, to the lining 8 of the car, which may be swung to lie on one of the reinforcing bars of the door sections to hold the doors in their inwardly swung positions, as indicated in Fig. 4, and when the doors are out of use and swung back as just described the upper and lower keys may be carried safely in one of their respective door sections by simply engaging 15 the key pins in the eyes of their respective section reinforcing bars.

From the foregoing description the manner in which the door is used and operated will be readily apparent as it will be seen 20 that to put the lower door into use all that is necessary is to raise the latches 82 clear and swing the doors into the closed position and insert the key 35 in the groove 18 with its pins engaging the eyes of the overlapping ends of the reinforcing bars. The door will then be closed and the car ready 25 to receive grain, and it should be particularly noted, as this is a most important feature of the device, that the dimensions of the sections 10 and 11 and of the key 35 30 are such that when assembled to form the complete door the sections do not lie in the same plane but incline slightly inwardly so that the door has when closed a camber 35 the crown of which is towards the inside of the car as shown in Fig. 2, so that while the pressure of the grain cannot force the sections open until the key is withdrawn it tends to tighten the walls of the groove on 40 the sides of the key and thus maintain the rigidity of the door. The same applies to the upper door which is closed and locked in the same way by the key 61. To open the lower door the hook 42 is dropped and engaged in the eye 41, the lever 69 and extension 70 are lowered to the position shown by the full lines in Fig. 4, so that the operator may reach in through the opposite doorway of the car and grasp the extension 45 when by giving the lever a few strokes to rotate the barrel 66 to tighten and pull up on the rope 74 the key 35 is raised to disengage its pins out of the eyed ends of the bars. Immediately the pins are clear of the eyes the pressure of the grain swings the sections 10 and 11 outwardly so that the car may then be unloaded, and it should be noted that the taper of the groove 18 and key 35 is designed so that the door 50 sections may open immediately the key has

been raised the amount required to disengage the pins so that a very small amount of vertical movement of the key is necessary.

The upper door sections may be opened 70 at will after the lower ones have been opened. When the door on the opposite side of the car is to be opened the bolt 80 is withdrawn and the bracket 76 and sheave 75 moved over to the other side to be supported in the slot 79 by the bolt 80, the rope 74 being passed around the barrel in the opposite direction, whereupon the opposite door may be opened by operating the lever 69 as described.

When it is desired to open the doors from a point distant from the car, say from an elevator alongside which the car is brought to be discharged, the pawl and ratchet mechanism with associated levers is mounted in a suitable place in the building and the rope 74 is passed through and provided with a snatch block so that by simply hooking the snatch block to any of the holes 81 in the sheave 75 and hooking the hook 42 in the eye 41 of the key the doors may be opened in the same manner as already described.

What I claim as my invention is:—

1. A door comprising two sections adapted to be disposed across the door opening with their adjacent vertical edges spaced apart, and means adapted to engage with said adjacent edges to maintain the door when closed in substantially camber-like formation.

2. A door comprising two sections adapted to be disposed across the door opening with their adjacent vertical edges spaced apart, and a vertically withdrawable key adapted to engage with said adjacent edges and to interlock with said sections for maintaining the door when closed in substantially camber-like formation.

3. A vertically divided car door including two swingable sections adapted to be disposed across the door opening with their adjacent vertical edges spaced apart, said sections being movable outwardly to completely open the car doorway or inwardly to lie on the car wall, and releasable means adapted to engage with the adjacent edges of said sections and to interlock with said sections for maintaining the door when closed in substantially camber-like formation.

4. A vertically divided car door including two swingable sections adapted to be disposed across the door opening with their adjacent vertical edges spaced apart, said sections being movable outwardly to completely open the car doorway or inwardly to lie on the car wall, and releasable means adapted to engage with the adjacent edges of said sections and to maintain the door when closed in substantially camber-like formation, said means

being also adapted to lock the adjacent edges of said sections together against inward or outward pressure, and means for releasing said releasable means to unlock the adjacent edges capable of operation at a point remote from the door.

5. A car door comprising a pair of door sections hinged at opposite sides of the car doorway and flanged at their free ends whereby when the sections are closing the doorway a vertical groove is formed by the opposed flanged ends, and a withdrawable key adapted to be seated in said groove to lock said sections together against inward or outward movement.

6. A car door comprising a pair of door sections hinged at opposite sides of the car doorway and flanged at their free ends whereby when the sections are closing the doorway a vertical groove is formed by the opposed flanged ends, and a withdrawable key adapted to be seated in said groove to lock said sections together against inward or outward movement, said key co-operating with said sections to maintain the complete door when closed in substantially camber-like formation.

7. A car door comprising a pair of door sections hinged at opposite sides of the car doorway and flanged at their free ends whereby when the sections are closing the doorway a vertical groove is formed by the opposed flanged ends, a withdrawable key adapted to be seated in said groove to lock said sections together against inward or outward movement, and means for locking the key in the groove.

8. A car door comprising a pair of door sections hinged at opposite sides of the car doorway and flanged at their free ends whereby when the sections are closing the doorway a vertical groove is formed by the opposed flanged ends, said groove being tapered downwardly and inwardly, and a withdrawable key adapted to be seated in said groove to lock the sections together against inward or outward movement, said key being tapered complementary to the taper of the said groove.

50. 9. A car door comprising a pair of door sections hinged at opposite sides of the car doorway and flanged at their free ends whereby when the sections are closing the doorway a vertical groove is formed by the opposed flanged ends, a withdrawable key adapted to be seated in said groove to lock the sections together against inward or outward movement, and means for withdrawing the key from the groove.

60. 10. A car door comprising a pair of door sections hinged at opposite sides of the car doorway and flanged at their free ends whereby when the sections are closing the doorway a vertical groove is formed by the opposed flanged ends, a withdrawable key

adapted to be seated in said groove to lock the sections together against inward or outward movement, means for locking the key in seated position in the groove, and means for withdrawing the key from the groove.

11. A car door comprising a pair of door sections hinged at opposite sides of the car doorway and flanged at their free ends whereby when the sections are closing the doorway a vertical groove is formed by the opposed flanged ends, a plurality of vertically eyed members secured to each section spaced vertically thereon, the eyed members of one section overlapping those of the other section with the eyes of the overlapped members in registration when the sections are in the closed position, and a withdrawable key adapted to be seated in said groove to lock the sections together, said key being provided with a plurality of pins adapted to engage respectively the registering eyes of the respective overlapping eyed members.

12. A car door comprising a pair of door sections hinged at opposite sides of the car doorway and flanged at their free ends whereby when the sections are closing the doorway a vertical groove is formed by the opposed flanged ends, a plurality of vertically eyed members secured to each section spaced vertically thereon the eyed members of one section overlapping those of the other section with the eyes of the overlapping members in registration when the sections are in the closed position, a withdrawable key adapted to be seated in said groove to lock the sections together, said key being eyed at its upper end and provided with a plurality of pins adapted to engage respectively the registering eyes of the overlapped eyed members, a barrel member rotatably mounted on the car structure, a pawl and ratchet mechanism for operating said barrel, a sheave rotatably mounted above the key, and a cable connected at one end to said barrel and having its free end passed through said sheave and provided with a hook adapted to engage the upper end eye of the key.

13. A car door comprising a pair of door sections hinged at opposite sides of the car doorway and flanged at their free ends whereby when the sections are closing the doorway a vertical groove is formed by the opposed flanged ends, and a withdrawable key adapted to be seated in said groove locking the sections together against inward and outward movement and co-operating with them to maintain the door in substantially camber-like formation, said key being gripped tightly by the groove walls to maintain the lock when the camber side of the door is under pressure.

14. A car door comprising a pair of door sections hinged at opposite sides of the car

doorway and flanged at their free ends whereby when the sections are closing the doorway a vertical groove is formed by the opposed flanged ends, said groove being tapered downwardly and inwardly, a plurality of eyed members secured to each section spaced vertically thereon, the eyed members of one section overlapping those of the other section with the eyes of the overlapped members in registration when the sections are in the closed position, and a withdrawable key adapted to be seated in said groove locking the sections together and co-operating with them to maintain the door in substantially camber-like formation and provided with a plurality of pins adapted to engage respectively the registering eyes of the respective overlapping eyed members, said key being gripped tightly by the groove walls to maintain the lock when the camber side of the door is under pressure, the grip being relieved to break the lock coincident with the disengagement of the said pins from the said eyes as the key is withdrawn.

15. A main car door comprising a pair of lower door sections hinged at opposite sides of the car doorway and flanged outwardly at their free ends whereby when the sections are closing the doorway a vertical groove is formed by the opposed flanged ends, said groove being tapered downwardly and inwardly, a withdrawable lower key adapted to be seated in said groove to lock the sections together tapered complementary to the groove and formed channel-like in section, a supplemental door comprising a pair of upper door sections hinged at opposite sides of the doorway flanged inwardly at their free ends whereby when the sections are closed a vertical groove is formed by their opposed flanged ends, said groove being tapered downwardly and inwardly, a withdrawable upper key adapted to be seated in the said upper groove to lock the upper sections together tapered complementary to the groove and formed channel-like in section, said upper door sections overlapping at their lower ends on the upper ends of the lower door sections and said upper key overlapping the lower key, and a filler secured to the upper end of the lower key adapted to close the space between the keys when overlapped.

In testimony whereof I affix my signature at Vancouver, B. C., Canada, this 8th day of April, 1922.

DANIEL ROBERT CAMERON.
